ERNEST C. WINGIRE, OF MINNEAPOLIS, MINNESOTA, ASSIGNOR OF ONE-HALF TO PETER J. N. MILLER, OF MILLER, SOUTH DAKOTA.

WIRE-STRETCHER.

1,202,464.

Specification of Letters Patent. Patented Oct. 24, 1916.

Application filed June 14, 1915. Serial No. 33,951.

To all whom it may concern:

Be it known that I, ERNEST C. WINGIRE, a citizen of the United States, residing at Minneapolis, in the county of Hennepin and State of Minnesota, have invented certain new and useful Improvements in Wire-Stretchers, of which the following is a specification.

This invention relates to stretchers and particularly wire stretchers and its main object is to provide a light and specially powerful stretcher that may be operated from the rear of the object to which it is attached and thus rendered entirely safe to the operator in case a breakage of the wire should occur.

Another aim of the invention is to so construct the device that the drive shaft thereof may be readily and quickly thrown out of gear with the winding drum, or other take up device, so as to permit of the pulling cable or connection being quickly unwound from the said drum.

The invention aims further to provide a device of this class so constructed that it may be quickly adapted for use in drawing together the ends of two wires to be spliced.

Another aim of the invention is to so construct the device that, when disposed against a post in position for use and during its operation, it will not have a tendency to work around the post, but, on the other hand, will maintain the position in which it is initially placed.

In the accompanying drawings: Figure 1 is a top plan view of the wire stretcher embodying the present invention. Fig. 2 is a side elevation thereof, the device being adapted for employment in drawing together the ends of two wires to be spliced.

Corresponding and like parts are referred to in the following description and indicated in all the views of the accompanying drawings by the same reference characters.

The device includes in its structure a substantially rectangular open frame including spaced sides 1 and 2, a forward end member 3 and a rear end member 4. This frame is provided further with an arm 5 which extends rearwardly from the end member 4 of the frame and substantially in alinement

with the side member 2 thereof. The arm 5 is provided upon its under side with a reinforcing web or flange 6 to the rear end of which is connected one end of a post encircling chain 7 or other flexible element designed to be engaged about a fence post against which the frame, above described, has been disposed, the post being partly received within the angle between the rear member 4 of the frame and the adjacent side of the said arm 5, as clearly shown in Fig. 1 of the drawings. The numeral 8 indicates a connecting clasp which is connected by a link, as at 9, to the rear end of the side 1 of the frame and this clasp is engageable interchangeably with the links of the chain 7, so that the chain may be drawn more or less tightly about the post and secured. Mounted for rotation in bearings 10 upon the sides 1 and 2 of the frame of the device is a shaft 11 having one end projecting beyond the side 1 of the said frame and squared, as at 12, for a purpose to be presently explained. Fixed upon the shaft 11 is a winding drum 13 to which is connected one end of a pull cable 14, the said cable being adapted to be wound upon the drum, when the drum is rotated, in one direction, as clearly shown in Fig. 1 of the drawings. The other end of the cable is connected, as at 15, to one member 16 of a wire grip, this member being formed with a fixed channeled gripping jaw 17 provided with a finger 18 designed to extend above or below a wire disposed within the channel of the said jaw, the said finger 18 serving to prevent accidental disengagement of the wire from the said grip. The grip device further includes a pivoted dog 19 having a gripping jaw portion 20 designed to coöperate with the channeled fixed jaw 17 in the manner clearly shown in Fig. 2 of the drawings.

Fixed upon the shaft 11 is a worm gear 20, the said gear being located between the winding drum 13 and the side 2 of the frame of the device. The said side 2 of the frame is formed or provided near its forward end with a bearing 21 and the arm 5 is provided upon its upper side and at its rear end with a bearing 22. The numeral 23 indicates the drive or actuating shaft of the device and

this shaft is increased in diameter near its rear end, as indicated at 24, and has its said portion 24 fitted rotatably and slidably or shiftably within the bearing 22. Near its forward end the shaft 23 is provided with a worm 25 and from the forward end of the worm to its forward extremity the shaft is reduced in diameter, as indicated at 26, so as to provide a shoulder designed to abut 10 against the rear end of the bearing 21, the said reduced portion 26 of the shaft being rotatably fitted within the said bearing. At its rear end the shaft 23 is squared as indicated at 27, and removably fitted to its said 15 end is an operating crank handle 28 which may be rotated for the purpose of rotating the shaft 23 and imparting rotary motion to the winding drum 13 through the medium of the gears 20 and 25. As before stated, the 20 portion 24 of the shaft 23 is shiftably as well as rotatably fitted within the bearing 22 and in a like manner the reduced portion of the shaft is shiftably fitted within the bearing 21. The forward shifting movement of the shaft is limited by the engagement of the shoulder at the forward end of the worm 25 against the rear end of the bearing 21 and the rearward shifting movement of the said shaft is limited by the engagement 25 of a stop pin or the like, indicated by the numeral 29, against the forward end of the said bearing 21.

By reference now to Fig. 1 of the drawings, it will be observed that the winding drum 13 is located in advance of that portion of the frame which is to be disposed against the fence post and that the operating crank handle 28 is located rearwardly of the said portion of the frame, and by 30 reason of this relative arrangement of the parts, the operator of the device may stand behind the fence post while operating the handle 28 and is therefore protected to a greater or less extent in the event of breaking 45 of the fence wire being stretched.

In the operation of the device, assuming that the pulling cable 14 has been unwound from the drum the desired portion of its length, and assuming that the shaft 23 is 50 shifted forwardly, or, in other words, occupies the position shown in full lines in the drawings, the rotation of the crank handle 28 will result in the drum 13 being rotated in a direction to wind up the pulling cable 14 and the pull exerted by this cable upon the gripping device will serve to stretch a wire laid between the jaws of the said gripping device. When the wire has been 55 stretched to the desired tension and has been brought to the desired position beside the fence post and has been secured to the said post, the pulling cable 14 may be quickly unwound from the drum 13 for application to another wire to be stretched by rotating

the crank handle 28 in an anti-clockwise direction, thus imparting corresponding rotary motion to the shaft 23 and the worm 25. As the worm 25 is rotated in the direction stated, it will gradually turn out of mesh with the gear 20, the shaft 23 moving 65 longitudinally rearwardly at the same time. When the worm 25 has been moved out of mesh with the gear 20, the pulling cable 14 may be quickly unwound from the drum 13 by pulling upon the said cable, as will be 70 readily understood. Of course, when it is desired to again rotate the drum 13 to wind up the pulling cable 14, the shaft 23 is shifted forwardly and at the same time the 75 crank handle 28 is rotated to the right, or in 80 a clockwise direction, and the worm 25 will in this movement of the crank handle and shaft feed into mesh with the worm gear 20 until the shoulder at the forward end of the worm abuts against the rear end of the bearing 21. It will further be noted by reference to Fig. 1 of the drawings that, due to the arrangement of the parts of the device, the wire being stretched may be brought much 85 nearer the post to which it is to be attached than is possible by the use of many of the present types of wire stretchers.

In order that the device may be employed in drawing the ends of two wires to be spliced, a wire gripping device 30 is attached to the rear end of the arm 5 and is adapted to grip one of the said wires, the other wire being gripped by the device which is attached to the end of the pulling cable 14. When the two wires to be brought 95 together have been connected with the gripping devices, the crank handle 28 is removed from the squared end 27 of the shaft 23, this shaft having been first shifted so as to bring the worm 25 out of mesh with the gear 20 100 and the said crank handle 28 is then applied to the squared end 12 of the shaft 11 and is rotated so as to wind the pulling cable 14 upon the drum 13.

It will be observed by reference to the 110 drawings that the winding drum of the device is supported in front of the post against which the stretcher is disposed and that the operating handle is arranged in the rear of the said post so that should the wire being stretched break, that portion thereof connected to the stretcher will strike the post and not the operator of the device.

Having thus described the invention, what is claimed as new is:

In a device of the class described, a frame constructed at one side for disposal against a post or the like and provided with an extension at its said side, a shaft rotatably mounted within the frame, a winding drum mounted upon the said shaft, a worm gear carried by the shaft, a bearing upon the frame, a bearing upon the extension in aline-

ment with the first mentioned bearing, a shaft rotatably and slidably mounted in the said bearings, a worm upon the shaft in gear with the worm gear, and means for rotating the last mentioned shaft, the last mentioned shaft being arranged when rotated in one direction to impart rotary mo-

tion to the worm gear and when rotated in the opposite direction to be shifted longitudinally through the unthreading of the 10 worm from mesh with the worm gear.

In testimony whereof I affix my signature.

ERNEST C. WINGIRE. [L. S.]
